UNITED STATES PATENT OFFICE.

JOHN L. WHEELER, OF ST. LOUIS, MISSOURI, ASSIGNOR TO SIMPLEX SHOE MACHINERY COMPANY, OF ST. LOUIS, MISSOURI, A CORPORATION OF MISSOURI.

SEWING MACHINE.

1,427,140.

Specification of Letters Patent. Patented Aug. 29, 1922.

Application filed November 23, 1917. Serial No. 203,516.

To all whom it may concern:

Be it known that I, JOHN L. WHEELER, a citizen of the United States, residing in the city of St. Louis and State of Missouri, have invented new and useful Improvements 5 in Sewing Machines, of which the following is a specification.

This invention relates to sewing machines, and, without being limited thereto, 10 has more particularly to do with machines for sewing leather and similar heavy material. It relates particularly to the thread-measuring and take-up mechanism and has for its principal object to secure and maintain 15 a uniform or constant definite tension on the thread.

In machines of this character the tension should be set and maintained with a 20 definite resistance on the thread to produce good results. Heretofore, spring-pressed tension devices have been employed. These require careful adjustment which, owing to the obvious nature of such constructions, is 25 difficult and troublesome to attain with exact nicety, often taking up considerable time, even by an expert operator; and after proper adjustment is effected the tension device frequently works loose or tightens or 30 is changed by the operator or someone meddling with the machine. This has been found to be the cause of imperfect stitching 35 or the breaking of the thread in many instances, which disadvantage is overcome by the present invention.

The invention consists primarily in the utilization of a weight-applied tension device of novel construction and arrangement, and, further, in the parts and combinations and arrangements of parts hereinafter 40 described and claimed.

In the accompanying drawing illustrating a practical embodiment of the invention,—

Figure 1 is a side elevation of a sewing 45 machine showing the thread-measuring and take-up mechanism and so much of the stitch-forming mechanism necessary to a full understanding of the operation thereof;

Figure 2 is a top plan view of the tension 50 device detached;

Figure 3 is a section on the line 3—3 of Figure 2;

Figure 4 is a face view of the thread-

wheel of the tension device, the supporting stud therefor being shown in cross section; 55 and

Figure 5 is a similar view of one of the clamping disks.

Referring now to the drawing, the numeral 1 indicates the standard or supporting column for the machine at the top of which is a bed-plate or table 2. On the bed-plate is the machine-head 3 at the front of which is a work-support 4. Co-operating with the work-support is a presser-foot 5 and 60 working through the work-support, in proximity to the presser-foot, is an arcuate needle 6 which is guided in its movement by a fixed guide-member 7 and a movable guide-member 8 mounted on the head 3. 70 All of these parts are embodied in the invention disclosed in Letters Patent granted to Myers and Wheeler, No. 1,188,474, and dated June 27, 1916. Hence, no further detailed description thereof will be herein 75 given other than to state that the needle carries a loop of the stitching thread through the work upon each reciprocation thereof and the loop is interlocked with a loop of a locking thread on the underside 80 of the work.

The stitching thread, indicated by the numeral 9, is taken from a source of supply (not shown), through the tension device to be presently described, and thence about the 85 thread-measuring, take-up and stitch-setting mechanism substantially as set forth in said Letters Patent aforesaid. This mechanism will now be described sufficiently to an understanding of the operation there- 90 of as far as it concerns the present invention.

On the top of the head 3 is a thread-clamping device 10 which is in the form a 95 hinged plate. Co-operating therewith is a lever 11 which is pivoted on the head 3, as at 12. At the upper end of this lever is an adjusting screw 13 which is arranged to bear against the device 10. The other end of the lever projects somewhat rearward from the head 3 and is provided with a roller 14 which is in the path of a cam-projection 15 on the periphery of a disk 16 fixed on the power shaft 17 of the machine.

Pivoted about the same axis as the lever 105 11 is a stitch-setting lever 18 at whose upper

end is a pulley 19, while at the opposite end thereof is a roller 20 which works in a cam-groove 21 formed in the face of the disk 16.

Pivoted on the bed-plate 2, as at 22, is a 5 thread-measuring lever 23 having a roller 24 which works in a cam-groove 25 formed in the face of the disk 16 opposite to that in which the groove 21 occurs. Pivoted, as at 10 26, near the upper end of the lever 23, is a supplemental arm 27 having a pulley 28 at its outer end on opposite sides of which are thread-guides 29. This arm 27 is limited in its movement by studs 30 on the lever 23, and it is yieldably held in the position shown 15 in the drawing by a spring-pressed pin 31 working in a tubular extension of the lever 23.

Secured to the head 3, as at 32, and having an arm 33 secured to the bearing bracket 20 34 for the power shaft 17, is a sector-bar 35 on which is an adjustable member 36 having a pulley 37 thereon, said member 36 being secured in position by a set-screw 38. At the end of the sector-bar 35 is a pulley 39. Both 25 of these pulleys 37, 39, have thread-guides 40 arranged on opposite sides thereof in a manner similar to the guides 29 which co-operate with the pulley 28 on the supplemental arm of the lever 23.

30 The operation of the mechanism will now be described. The stitching thread 9 is carried through the tension device and from there is taken around the pulley 39, thence about the pulley 37, pulley 28, under the 35 clamping device 10, over a pulley 41 at the upper front corner of the head 3, through a waxing device 42, over the pulley 19, and over a pulley 43 to the eye of the needle 6 which takes it through the work indicated 40 by the numeral 44.

The several cams on the disk 16 are so arranged and timed that during the time the needle is entering and receding from the work, the stitch-setting lever 18 is in a position with its end, on which is the pulley 19, lowered so that the thread is slack. After the needle has left the work and is continuing its upward travel the lever 23 is actuated, moving rearward rapidly. This 45 combined movement of the needle and the lever 23 pulls the thread until the stitch is just ready for setting, the spring-pressed pin 31 permitting the supplemental arm 27 to yield so as not to draw the stitch too tight, or in other words so as not to draw the interlooped stitching and locking threads into the puncture in the work. At this stage, the clamping device 10 is pressed by the lever 11, thereby locking the thread. 50 The thread being thus clamped, the continued rearward movement of the lever 23 pulls sufficient thread through the tension device; and at the same time the stitch-setting lever 18 is actuated to pull the inter-looped portions of stitching and locking 55

threads into the puncture in the work, or in other words, to set the stitch. Just before the needle starts again on its downward stroke, the thread-clamping device 10 is released and the lever 23 moves to its forward 70 position so as to slacken the thread between the clamping device and the pulley 37.

Now, it is essential that the tension device through which the thread is taken from the source of supply be set and maintained constantly with a predetermined or given resistance to assure the perfect working of the thread-measuring and take-up mechanism. As before pointed out, spring-pressed tension devices have proven unreliable owing 80 to the possibility of adjustment and accidental change. Hence, the present invention contemplates the production of a device which may be properly proportioned and set at the factory and is non-adjustable, so that 85 there is little liability of it being accidentally or intentionally changed after the original installation.

As shown in the drawing, the device comprises an angular block 45 having a base 90 portion 46 and an upstanding portion 47. From the upstanding portion extends a stud 48 which is flattened on one side, as at 49. On this stud is rotatably mounted a peripherally grooved thread-wheel 50 on opposite 95 sides of which are two clamping disks 51, the central opening of said disks being flattened correspondingly to the flattened portion 49 of the stud so as to be non-rotatable thereon. Between the clamping disks and 100 the thread-wheel, felt or fibre washers 52 are interposed. A collar 53 is sleeved loosely on the stud between the portion 47 of the block 45 and the inner clamping disk, while a second collar 54 is likewise mounted 105 on the stud next to the outer clamping disk.

The angular block 45 is slotted, as at 55, 56, and has pivoted therein, as at 57, a bell-crank, one of whose arms 58 extends upward and is bifurcated, as at 59, so as to straddle 110 the end portion of the stud and bear against the outer face of the collar 54. The other arm 60 of the bell-crank extends substantially horizontal and has a weight 61 suspended from its outer end, preferably as 115 shown. That is, by perforating the arm and providing the weight with a hook or loop for engagement therewith. In this way the perforation may be located at the proper distance from the fulcrum point of 120 the bell-crank and the weight proportioned to give the desired pressure on the tension wheel, thereby maintaining a constant given tension on the thread. If it is necessary to release the tension at any time the operator 125 has only to raise the arm 60 of the bell-crank; and as soon as the arm is let go, the weight is again effective to restore the tension. The thread-wheel and its associated elements which are mounted loosely on the 130

stud 48 also gives a certain amount of flexibility to the device. That is, the thread-wheel is permitted to wobble somewhat without disturbing the tension to any appreciable degree when undue lateral force is exerted near the periphery of the wheel.

The tension device may be mounted on the machine at any desirable or convenient place and in any desirable manner. As shown, 10 the block 45 is secured on a bracket extension 62 of a plate 63, and the plate is secured to the end portion of the bed-plate 2 of the machine by bolts or screws 64, said plate having a lug 65 at its end arranged 15 and adapted to project under the edge of the bed-plate 2 to relieve the strain on the bolts or screws 64 when the weight 61 is applied.

Obviously, the tension device admits of considerable modification without departing 20 from the spirit and scope of the invention as defined in the appended claims. The invention, therefore, is not limited to the construction and arrangement shown in the accompanying drawing.

25 What is claimed is:

1. In a sewing machine, stitch-forming mechanism, a thread-measuring and take-up mechanism operating in conjunction with said stitch-forming mechanism, a tension device through which the thread passes between the source of thread supply and said thread-measuring mechanism, and a pressure device for said tension device including a lever having a weight in a predetermined 35 fixed position thereon.

2. In a sewing machine tension, a thread-wheel, and means for exerting a constant, uniform, resisting pressure on said wheel,

said means comprising a lever, one arm of which bears against said wheel substantially 40 axially thereof, and the other arm having a weight in predetermined, non-adjustable position thereon.

3. In a sewing machine tension, a thread-wheel, a clamping disk having endwise 45 movement but being non-rotatable with respect to said wheel, and means for exerting a constant, uniform, resisting pressure on said wheel, said means comprising a lever, one arm of which bears substantially axially 50 against said disk and wheel, and the other arm having a weight thereon in predetermined non-adjustable relation to the pivotal axis of the lever.

4. In a sewing machine tension, a supporting member, a stud thereon, a thread-wheel mounted loosely on said stud so as to rotate and wobble, clamping disks mounted on said stud, on opposite sides of said thread-wheel, said disks being non-rotatable 60 but capable of endwise movement and wobbling, bearing collars mounted loosely on said stud, one of said collars being interposed between the inner clamping disk and said supporting member and the other collar 65 being next to the outer clamping disk, the disk-engaging end portions of said bearing collars being tapered, and a lever mounted on said supporting member, one arm of said lever bearing against the outer collar and 70 the other arm having a weight in predetermined, non-adjustable position thereon.

In testimony whereof, I have hereunto set my hand.

JOHN L. WHEELER.
